Primary Examiner — George D. Kirschbaum*Assistant Examiner* — Lillian Embrey(74) *Attorney, Agent, or Firm* — Dunlap Bennett & Ludwig, PLLC; Anna L. Kinney(57) **CLAIM**

The ornamental design for a spacing jig for lap siding, as shown and described.

DESCRIPTION

FIG. 1 is a top front perspective view of a spacing jig for lap siding, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict boundaries around portions of the spacing jig for lap siding that form no part of the claimed design.

1 Claim, 5 Drawing Sheets(56)
